UNITED STATES PATENT OFFICE.

ALLAN EDMONDSON, JOHN BENJAMIN MOORHOUSE, AND THOMAS ABRAHAM PROCTER, OF SKIPTON-IN-CRAVEN, COUNTY OF YORK, ENGLAND.

HINGE FOR STEP-LADDERS.

SPECIFICATION forming part of Letters Patent No. 357,188, dated February 8, 1887.

Application filed September 20, 1886. Serial No. 214,100. (No model.) Patented in Eng'nd July 10, 1885, No. 8,339.

To all whom it may concern:

Be it known that we, ALLAN EDMONDSON, JOHN BENJAMIN MOORHOUSE, and THOMAS ABRAHAM PROCTER, subjects of the Queen of Great Britain, all residing at Skipton-in-Craven, in the county of York, England, have invented a new and useful Improvement in Hinges for Step-Ladders, (for which we have obtained a patent in Great Britain, No. 8,339, bearing date July 10, 1885,) of which the following is a specification.

Our invention relates to an improvement in the hinges of step-ladders, the object of which, when the said step-ladders are opened, 15 their supports being extended, as when in position for being used, is to firmly hold them so, thus preventing any accidents incident to the slipping or moving too far outwardly or inwardly from or to the said step-ladders of 20 their supports, as has often been found to happen heretofore. This object is attained by the device illustrated in the accompanying drawings, in which—

Figures 1 and 2 are side views of the hinge 25 closed and opened, respectively, Fig. 3 being a plan of Fig. 1, while Fig. 4 is a perspective drawing of a step-ladder and hinge, in each case with our improved appliance attached.

Like letters of reference indicate like parts 30 in all the drawings.

The parts *a* *b*, hinged together at *c*, constitute the hinge commonly in use, and, according to our invention, to the part *a* we hinge the link *d* by means of the button-headed pin 35 *e*. In the said link *d* we form a slot, *f*, the

outer end of which terminates in the notch *g*. Of course it will be easily seen that the notch *g* may be formed either at the end, as shown, or at any distance therefrom, or even be supplemented by several other notches along the 40 upper edge of the said slot *f*.

To the part *b* we attach the button-headed pin *h*, the shank part of which passes through the slot *f*, which allows the parts *a* and *b* to open and close by allowing the pin *h* to pass 45 along it, and with the link *d* laying hold of the pin *h* by its notch *g* when the said parts *a* and *b* are apart, as shown by Figs. 2 and 4, the object desired is accomplished. When the said parts *a* and *b* are required to be closed, 50 by simply lifting the link *d* with its notch *g* clear of the shank of the pin *h* they are at liberty so to be.

Having now described the nature of our invention, what we claim is—

1. In combination with a step-ladder hinge, a slotted and notched link pivoted to one of the elongated portions of said hinge, in order to operate, substantially as herein specified.

2. In combination with a step-ladder hinge, 60 a slotted and notched link hinged thereto, operating with a pin attached to the said hinge in the manner and for the purposes specified.

ALLAN EDMONDSON.
JOHN BENJAMIN MOORHOUSE.
THOMAS ABRAHAM PROCTER.
